UNITED STATES PATENT OFFICE.

LOUIS J. COBLENTZ, OF NEW YORK, N. Y., ASSIGNOR TO LEON WEIL, INC., OF NEW YORK, N. Y., A CORPORATION OF NEW YORK.

DESIGN FOR A LADY'S SLIPPER OR SIMILAR ARTICLE.

Application filed December 23, 1925. Serial No. 15,835. Term of patent 3½ years.

To all whom it may concern:

Be it known that I, LOUIS J. COBLENTZ, a citizen of the Republic of France, and a resident of New York city, in the county and State of New York, have invented a new, original, and ornamental Design for Lady's Slipper or Similar Article, of which the following is a specification, reference being had to the accompanying drawing, forming part thereof.

The figure is a perspective view of a lady's slipper or similar article, showing my new design.

The novelty of the design resides more particularly in the modified form of a slipper vamp arranged to accommodate the specific design of buckle shown in the drawing.

I claim:

The ornamental design for a lady's slipper or similar article, substantially as shown and described.

LOUIS J. COBLENTZ.
